UNITED STATES PATENT OFFICE.

WILLIAM R. FOWLER, OF PHILADELPHIA, PENNSYLVANIA, ASSIGNOR TO
MARTIN J. MYERS, OF SAME PLACE.

CLOTH-CUTTING MACHINE.

SPECIFICATION forming part of Letters Patent No. 245,149, dated August 2, 1881.

Application filed June 11, 1881. (No model.)

To all whom it may concern:

Be it known that I, WILLIAM R. FOWLER, a citizen of the United States, residing in Philadelphia, Pennsylvania, have invented certain 5 Improvements in Cloth-Cutting Machines, of which the following is a specification.

My invention relates to certain improvements in the cloth-cutting machine for which Letters Patent were allowed to me on the 8th day of 10 April, 1881, the present improvements relating to certain details in the construction of the apparatus, with the object of simplifying its construction and increasing its efficiency, all as hereinafter fully set forth.

15 In the accompanying drawings, Figure 1, Sheet 1, is a perspective view of the cloth-cutter embodying my improvements, a portion only of the cloth-supporting table or bed being shown. Fig. 2, Sheet 2, is a side view, 20 partly in section and drawn to a larger scale, of the knife and knife-frame with a portion of the supporting-arm; Fig. 3, a sectional plan on the line 1 2, Fig. 2; Figs. 4 and 5, detached views of parts of the device, and Figs. 6 and 25 7 views of instruments which are used in connection with the cutting device.

The machine is similar in principle to that above alluded to, the cloth-supporting bed A consisting of wires projecting vertically from 30 a suitable backing and spaced so as to permit the free traversing through the bed in any direction of the cutting-knife B, the latter being adapted to cut on the upward stroke, and the cloth or other material being pressed thereby 35 against an abutment-plate, D, which rests on and is moved over the surface of the said material. The knife B, which I use in the present instance, however, is widest at and near the cutting-edge x, and is reduced in width at 40 the lower end, the object of this arrangement being to permit the free turning of the knife in the bed without the necessity of limiting the width of the cutting-edge, the wide portion of the knife, when the latter is in the bed, 45 occupying a position adjacent to the elastic upper ends of the wires, which are free to yield when the knife is brought into contact with the same, while the narrow lower end of the blade, which occupies a position adjacent to 50 the comparatively rigid bases of the wires, is

of less width than the spaces between the wires, and consequently meets with no opposition in turning. The reciprocating movement of the knife also facilitates the turning of said knife in the bed, as the period of contact of the wide 55 upper end of the knife-blade with the wires is so short that said wires exercise no appreciable resistance to the turning of the blade.

The knife has a shank, a, which is adapted to a stem, b, the latter embracing the shank of 60 the knife and being provided with a transverse screw or pin, which can be adapted to any one of a series of openings, a', in the said knife-shank, so that the latter can be adjusted vertically in respect to the stem b to compensate 65 for wear. (See Fig. 4.)

The stem b is secured to a block, d, which is adapted to a vertical guiding-slot in a frame, E, and a tubular journal, e, on the latter is adapted to an opening in a projection, f, on 70 the end of an arm, F, the journal e being provided with a collar or nut, e', so that, while it is secured vertically to the arm F, it is free to turn in the projection f of said arm on manipulating a handle, G, with which the frame E is 75 furnished. The stem of this handle projects through a slot in a vertical standard of the abutment-plate D, so that the latter can be adjusted vertically in respect to the frame E, to accord with the thickness of the pile of 80 cloth to be cut, the plate being secured in position after adjustment by tightening a nut, g, on the threaded stem of the handle.

Stability of the plate D is insured by providing the meeting-faces of the standard and 85 frame E with notches and projections, the notches of one part receiving the projections of the other part, and thus securely locking the parts in position after adjustment.

The knife B passes through a slot in the 90 plate D, and the latter has a casing, h, which protects the cutting-edge of the knife when the latter rises above the cloth, injury to either the attendant or the knife being thus prevented.

On the inside of the casing h are straps i, which serve to retain masses of absorbent material, the lower ends of which rest on the plate D and serve to absorb any oil which may find its way to said plate from the bearings above, 100

the soiling of the cloth by this oil being thus prevented.

The projecting portion of the plate D is made in skeleton form, being grated in the present instance, so that while sufficient bearing-surface is presented the plate does not materially obstruct the view of the lines marked on the surface of the cloth.

The arm F, which carries the knife-guiding frame E, is pivoted to an arm F', and the latter is hung to a fixed vertical standard, J, which is secured to the floor of the room adjacent to one side of the table A, the latter being preferably mounted on wheels or casters, so that it can be moved longitudinally in respect to the standard J, so that when one portion of the cloth within the sweep of the arms F F' has been acted upon the table may be readjusted and a fresh portion brought under the action of the knife.

To prevent excessive strain on the pivot-pin of the arm F', said arm is furnished with anti-friction rollers m, which are adapted to a segmental track, n, on the standard J, and serve to support the arms F F' in their proper horizontal plane above the table A.

Power is transmitted from a shaft, K, to the knife in the following manner: A belt, p, passes round a pulley, s, on said shaft K, thence over idlers s' s', carried by the arm F', and thence round a pulley, t, which is secured to a shaft, k, forming the pivot-pin of the arms F F'. This shaft k also carries a bevel-wheel, t', which gears into a pinion, t'', on one end of a shaft, M, the latter being adapted to bearings in the arm F, and being provided at its front end with a disk having a crank-pin which is connected by a suitable rod, v, to a sleeve, v', fitting between collars v'' on a rod, N, so that the latter is reciprocated vertically by, but is free to turn independently of, the sleeve v'. The rod N carries the knife-block d, and is adapted to bearings in the tubular journal of the frame E and in a projection, f', of the arm F, as shown in Fig. 2. The stem b occupies a position in the rear of the rod N, so that the center line of the said rod will be in line, or thereabout, with the center of the cutting-edge of the knife B, and the latter will not project unduly on either side of the axis of rotation. This construction is not essential, however, and is merely adopted as a matter of convenience.

In order to permit convenient access to the knife, as well as to facilitate the action of cutting strips in the manner described hereinafter, I discontinue the bed A some distance from the frame of the table at one side, so as to leave a channel or passage, w, Fig. 1.

In cutting small pieces of cloth it is sometimes necessary to apply pressure to the top of the same, in order to retain them upon the bed and prevent them from being pushed along by the knife as the latter is traversed through the bed. In order to conveniently effect this I provide the instrument shown in Fig. 6, which consists of an elastic strip or rod bent so as to

form a handle, P, with two projecting prongs, P', the latter being adapted to rest on the surface of the cloth and hold the latter on each side of the knife, and as closely to the latter as may be desired, the elasticity of the strip permitting the contraction of the prongs P' to any required extent. The under sides of the prongs may, if desired, be roughened to afford a firmer hold on the cloth.

For cutting strips I use a guide-rod, S, (Fig. 7,) this guide-rod being pivoted to a frame, T, which is adapted to the upper edge of the frame of the table, and is free to slide longitudinally thereon. The angle of the rod S in respect to the frame T is determined, and the securing of said rod in position after adjustment is effected by means of a brace, S', also pivoted to the frame T, but slotted at the outer end for the reception of the stem of a thumb-screw, y, on the arm S.

The guidance of the knife-carrier by the arm S is effected through the medium of a forked plate, W, secured to the standard of the plate D, and having recesses for the reception of a flange on the rod S, as shown in Fig. 5, the plate W being adjustable vertically in the same manner as the plate D, and being retained in position by the nut g after adjustment.

The width of the cut strips is determined by an adjustable gage, V, which is hung to the frame T, and which bears on the edge of the layers of cloth on the bed, the distance of the gage from the knife determining the width of the strips, which, after each cut, are removed and the frame T readjusted until the gage bears against the freshly-cut edge of the cloth, when it is secured in position prior to making another cut. During the adjustment of the frame T the knife occupies a position in the passage or channel w.

I claim as my invention—

1. The within-described cutting-knife, consisting of a blade having a cutting-edge, x, adapted to cut on the upward stroke, and having the portion below said edge reduced in width, so as to present a narrow tongue at and near the lower end of the blade, as set forth.

2. The combination of a cutting-bed composed of upright elastic projections, a plate adapted to bear on the surface of the cloth or other material to be cut, and a knife reduced in width so as to present a narrow tongue at and near the lower end, said knife having a cutting-edge, x, adapted to cut on the upward stroke, as set forth.

3. The combination of the arm F, the knife-guiding frame E, its handle, stem, and nut g, and the plate D, having a vertically-slotted standard, as set forth.

4. The combination of a cutting-bed, substantially as described, a knife adapted to cut on the upward stroke, and an abutment-plate, D, of skeleton form, as set forth.

5. The combination of the abutment-plate D with holders of absorbent material, as set forth.

6. The combination, in a cloth-cutting ma-

chiae, of the standard J, having a segmental track, n, with the arms F F', and the rollers m, as specified.

7. The combination of the standard J, arms F F', shaft K, pulleys s, s', and t, bevel-wheels t' t'', and shafts M and k, as set forth.

8. The cloth-supporting bed, having a passage or channel, w, at one edge, as set forth.

9. The work-holding device, comprising a handle, P, with elastic prongs P', as set forth.

10. The combination of the knife-carrier with the guiding-rod S, bracing-rod S', and adjustable frame T, as specified.

11. The combination of the guide-rod S and

adjustable frame T with the gage V, as set forth. 15

12. The combination of the guide-rod S with the knife-carrier, having the guide-frame W, as set forth.

13. The combination of the plate D and the knife with the shield h, as set forth. 20

In testimony whereof I have signed my name to this specification in the presence of two subscribing witnesses.

WM. R. FOWLER.
